(57) CLAIM

The ornamental design for a card case, as shown and described.

DESCRIPTION

1. Card case

1.1 : Front

1.2 : Back

1.4 : Right

1.5 : Top

1.6 : Bottom

1.7 : Perspective

1.8 : Bottom view of card case in an alternate position

1.9 : Top view of card case in an environment of use

The features illustrated in evenly-spaced dashed lines are included for illustrative purposes only to depict the environment of the card case and form no part of the claimed design.

1 Claim, 9 Drawing Sheets(56)
